UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

DOUBLE-DRUM HOIST.

Application filed July 15, 1926. Serial No. 122,676.

This invention relates to double drum hoists of the type in which one drum or the other is automatically connected to be driven from a reversible motor in accordance with 5 the direction of rotation of the motor.

The object of the present invention is to enable a double ended rocking pawl or clutch member to be mounted on a main driver located at one end of one of the drums 10 so that the pawl may rock through a plane offset from and paralleling the axis of rotation of the drive shaft.

Other objects will appear hereinafter.

The invention is illustrated in one of its 15 preferred forms in the accompanying drawings, in which

Figure 1 is a sectional elevation of a hoist,

Figure 2 is a transverse sectional elevation taken through Figure 1 on the line 20 2—2 looking in the direction of the arrows, and

Figure 3 is a plan view partly in section taken through Figure 2 on the line 3—3 looking in the direction of the arrows.

25 Referring to the drawings, A designates a base plate of the hoist on the opposite ends of which are mounted end frames B and C. The end frame C in this instance also serves as a housing for a motor D of the flat piston type, sometimes called the "Dake" motor. The invention, however, is not confined to the particular type of motor illustrated and any suitable reversible motor may be substituted therefor. In this instance a valve 30 chest E secured to the end frame C by means of suitable bolts F serves as a closure for one side of the motor D.

Pressure fluid for actuating the motor D is conveyed to the valve chest E through a 40 connection G and the distribution or admission of such pressure fluid to the motor may be controlled by any suitable valve (not shown), intended to be actuated by a reversing lever H. The frames B and C in this instance are braced at their upper ends by a tie rod J which extends through the frames and is provided with nuts K at its ends for clamping the rod to the frames.

45 A hollow center bearing L supported at one end in the frame B extends longitudinally of the hoist and carries at its other end a flange or plate O which forms a closure for one side of the motor D. The plate O is secured to the end frame C by the bolts 50 F which extend through the end frame C

and are screwed into the plate O. By thus securing the center bearing L in the manner described, the frames B and C are rigidly supported and braced with respect to each other and in addition a substantial bearing 60 is provided by the center bearing for a haulage drum P and a tail rope drum Q mounted side by side. An extension R is formed on the haulage drum P and has clutch teeth S of any well known type which interlock 65 with similar clutch teeth T carried by a sleeve U of a toothed drum driver V for transmitting rotary movement of the said drum driver to the drum P. The sleeve U of the drum driver V is in this instance of 70 the same external diameter as the extension R wherewith it cooperates to form a full bearing for the tail rope drum Q.

Suitable means are provided for checking or retarding rotation of the drums whenever one drum or the other of the drums is disconnected from the driving element. To this end the drum Q is provided with an annular lateral flange W and the drum P has a flange Y on which are mounted brake 80 bands Z and b. The brake bands Z and b are preferably of the type which encircle the flanges W and Y and may be manipulated in any suitable and well known manner.

85 In the present instance a main drive shaft c extends coaxially through the center bearing L and is connected at one end to the motor by a crank pin d. The other end of the drive shaft c is supported in the end of the center bearing by an anti-friction bearing e. A similar anti-friction bearing is also provided for the drive shaft c for the end of said drive shaft adjacent the motor. To the outer end of the drive shaft c is 90 keyed a driving pinion f which is rotatable in a gear box g in the frame B and meshes with an intermediate gear h mounted on a shaft j. The shaft j in this instance is provided at its ends with anti-friction bearings 95 k and o supported by the frame B and carries at its inner end a pinion p which meshes with an internal gear q of a main driver r.

100 In accordance with the present invention a bearing s is formed on the main driver r to rotate in a plane between the drum driver V of the drum P and an opposed drum driver t carried by the drum Q and arranged concentrically with respect to the drum driver V, the drum drivers V and t in this 105 110

instance being adapted to rotate in the same transverse plane. On the opposite sides of the bearing s are arranged pawl members u and v . These members are preferably of symmetrical formation and are arranged to extend in opposite directions so that the pawl is in effect a double ended pawl. These pawls are preferably held in assembled position and pivoted on the bearing s by a bolt w which extends therethrough and is provided with a suitable nut x whereby the pawls u and v are clamped in position. The bolt w is preferably disposed radially with respect to the longitudinal axis of the main driver r , so that the pawls u and v will oscillate in planes parallel with respect to each other and with respect to the axis of rotation of the main driver.

In order to prevent relative movement between the pawls u and v and the bolt w , key slots y are formed in the pawls to cooperate with keys z seated in the bolt w . The bolt w in this instance extends radially from the drive shaft c and in this way the pawls u and v are caused to oscillate in a plane offset from and paralleling the axis of rotation of the drive shaft.

In the operation of the hoist, let it be assumed that it be desired to connect the haulage drum P to be rotated by the main driver R . The lever H and consequently the throttle valve may then be moved to a position for actuating the motor in the required direction, in this instance, in a clockwise direction as Figure 1 is viewed from the right. The main driver r will then, due to the train of gearing which connects it with the driving shaft c , be caused to rotate in a counter-clockwise direction thus causing the pawl v to engage one of the teeth of the drum driver V and the drum P will remain interlocked with the main driver until the motor is again reversed. Upon reversal of the throttle lever H and consequently the motor D , the main driver will be caused to rotate in the opposite direction to rotate the drum Q . The reversal of the main driver will cause the pawl v to be forced out of engagement from the drum driver V and the pawl u will be simultaneously connected with the drum driver t carried by the tail rope drum Q .

In hoists of this type, it frequently happens that one of the pawl members is subjected to greater wear than the other pawl member, so that at times, depending upon the type of pawl used, it becomes necessary to discard the entire pawl although one portion thereof might be capable of rendering service for a considerably greater length of time. Owing to the fact, however, that there has no provision been made to permit such pawls to be reversed in the hoist, the entire pawl assembly will have to be discarded and a new pawl substituted therefor.

This adds to the expense of maintenance of the hoist and at times greatly interferes with the service for the reason that such parts are not at all times readily available. By forming the pawl members separately as in the present instance, these members may be interchanged one for the other in case one of the pawls show signs of greater wear than the other, or a new pawl may be substituted for the worn pawl.

I claim:

1. In a hoist, the combination of end frames, a center bearing supported by the end frames, a drive shaft extending through the center bearing, a reversible motor for rotating the drive shaft, a pair of drums rotatable relatively to the drive shaft, concentrically arranged drum drivers associated with the drums, said drum drivers rotating in the same transverse plane, a main driver rotatable on the center bearing connected to be rotated by the drive shaft, and a double ended pawl carried by the main driver to engage one or the other of the drum drivers in accordance with the direction of rotation of the said main driver, said pawl oscillating about an axis radial to the axis of rotation of the drive shaft.

2. In a hoist, the combination of end frames, a center bearing supported by the end frames, a drive shaft extending through the center bearing, a reversible motor for rotating the drive shaft, a pair of drums rotatable relatively to the drive shaft, concentrically arranged drum drivers associated with the drums, said drum drivers being located at one end of the drums and adapted to rotate in the same transverse plane, a main driver rotatable on one end of the center bearing connected to be rotated by the drive shaft, and a double ended pawl carried by the main driver to engage one or the other of the drum drivers in accordance with the direction of rotation of the main driver, said pawl oscillating about an axis radial to the axis of rotation of the drive shaft.

3. In a hoist, the combination of end frames, a center bearing supported by the end frames, a drive shaft, a reversible motor for rotating the drive shaft, a pair of drums rotatable relatively to the drive shaft, concentrically arranged drum drivers associated with the drums and rotating in the same transverse plane, said drum drivers being located at one end of one of the drums, a main driver rotatable on one end of the center bearing connected to be rotated by the drive shaft, a bearing integral with the main driver, pawls on opposite sides of the bearing and extending in opposite directions to engage one or the other of the drum drivers in accordance with the direction of rotation of the main driver, a bolt extending through the pawls and the bearing to form a pivot for the pawls, said bolt being dis-

posed radially with respect to the main driver, and means for locking the pawls to the bolt.

4. In a hoist, the combination of end frames, a center bearing supported by the end frames, a drive shaft, a reversible motor rotating the drive shaft, a pair of drums rotatable relatively to the drive shaft, concentrically arranged drum drivers associated with the drums and rotating in the same transverse plane, a main driver rotatable on one end of the center bearing connected to be rotated by the drive shaft, a bearing integral with the main driver, a bolt in the

bearing and disposed radially with respect to the main driver, pawls secured to the bolt on opposite sides of the bearing and extending in opposite directions to engage one or the other of the drum drivers in accordance with the direction of rotation of the main 20 driver, the pawls oscillating in planes parallel with respect to each other and with respect to the axis of rotation of the main driver.

In testimony whereof I have signed this 25 specification.

EARL B. LEAR.
